FLOOR-DRESSING IMPLEMENT.

1,176,355.

Specification of Letters Patent.

Patented Mar. 21, 1916.

Application filed June 29, 1914. Serial No. 848,040.

To all whom it may concern:

Be it known that I, EDGAR D. FITZWATER, a citizen of the United States, and a resident of Indian View, in the county of Hamilton and State of Ohio, have invented a certain new and useful Improvement in Floor-Dressing Implements, of which the following is a specification.

This invention relates to floor-dressing implements and more particularly, to a hand-operating device that is adapted to receive and carry or propel a smoothing plane or the like along and in contact with a floor or like surface to be scraped, smoothed or likewise finished or dressed, and the object of the invention herein is to provide a smoothing plane or the like with a carrier frame or box from the bottom of which latter it projects slightly and a suitable rearwardly-projecting handle or lever that slants upwardly and is pivotally-connected to the carrier-frame to propel or manipulate the entire device along and in contact with the surface to be smoothed or likewise finished or dressed.

The details of construction will be fully hereinafter described and then particularly pointed out in the claims.

In the accompanying sheet of drawings, Figure 1 is a plan view showing the device with a smoothing-plane therein only; Fig. 2, a longitudinal sectional elevation taken on a line near one edge of the plane and the manipulating-handle; Fig. 3 a transverse section taken on a line with the fore end of the plane, and showing the manipulating-handle broken off; Fig. 4, a side elevation of the device seen in Figs. 1, 2 and 3, but with the manipulating-handle omitted; Fig. 5, a plan view of Fig. 4 but with the plane omitted and showing, however, a scraper-attachment at the fore end of the carrier-frame; Fig. 6, a longitudinal section of the carrier-frame and the scraper seen in Fig. 5, omitting the plane; Fig. 7, a longitudinal section of the form of sand-papering block I wish to use in my device when the plane and scraper are omitted; and Fig. 8, a plan view of the said sand-papering-block, showing the bottom-side thereof.

1 indicates a carrier frame or box having an elongated longitudinal opening 2 which is narrowest at its upper portion and broadest at its lower portion to provide suitable

intervening shoulders 3, the latter being made at a reduced height at their rear ends, as best shown at 4 in Figs. 2 and 6. This carrier-frame is preferably made of metal or material that imparts weight enough to the device to facilitate its use on a surface to be dressed, and its fore end is made somewhat thinner than its other walls (as in Figs. 1, 2, 5 and 6) to permit close work in corners and toward side-walls of a room in which the floor is being dressed. The rear end of the carrier-frame is higher than its fore portion, as shown at 5, and is thus better adapted for the attachment of the manipulating-handle 6, the latter having forked fore ends 7 that are each pivotally-attached to the side-walls of the carrier-frame by means of a short shouldered screw-bolt 8 and adjusting lock or set screw-bolts 9 that respectively engage the series of openings 10 in the high portion 5 of the side-walls of the carrier-frame (see Fig. 4) for arranging the main or outer portion of the manipulating-handle 6 at the desired slanting angle or inclination to suit the height of the operator who walks back and forth along the floor in pushing the implement to bring the bit or blade 11 of the plane 12 into cutting action, thus saving himself the extremely difficult and tiring task of getting on his knees to handle the plane.

The plane 12 is of the ordinary smoothing type and has its rear end reduced in height to provide the upper shouldered portion 13 that alines beneath the lower, rear shouldered portion 4 on the inner faces of both side-walls of the carrier-frame, as best seen in Fig. 2.

Short bolts 14 are used to connect the outer ends of the forks 7 in place at the inner end of the slanting manipulating-handle 6, as best seen in Figs. 1 and 2.

In using my device, the plane is first set upright on the floor and then the carrier-frame is placed vertically upon it so that it (the plane) shall engage and lie within the elongated opening 2 and with the main or fore end of the plane-stock having its side edges supporting the shouldered portions 3 within said elongated opening 2. A suitable or ample space 15 is provided between the rear shouldered portion 13 of the plane-stock and the lower rear shouldered portion 4 on the inner face of both the side-walls of the

carrier-frame so that the latter may have a slight rocking movement on the plane to allow for inequalities or unevenness in the surface to be dressed, such compensation preventing the vibration of the plane and any "skipping" of the sharp edge of the bit or blade along said surface. This "skip" prevention feature is an important one as it enables the device to be freely and effectively used along surfaces that are quite rough and uneven, and the handle can be readily manipulated in passing the device to and fro or straight ahead with a natural or normal swing of the arm without imparting that swing to the plane to throw its lower face away from cutting or dressing contact. The lower face of the carrier-frame is slightly elevated above the floor surface so as to free the plane from any undue friction or resistance beyond that of its own lower surface only along the floor surface to be dressed. This feature is clearly shown in Fig. 2.

In Figs. 5 and 6 I show a convenient form of scraper device adapted to be used in my machine, especially when the smoothing-plane has been removed and an unusually rough surface is to be dressed or prepared for the said plane. A triangular cross-section base or block 16 is detachably secured by means of screw-bolts 17 to the thin front wall of the carrier-frame and a scraper-blade 18 is detachably as well as adjustably secured to the inwardly-beveled surface of said block 16 by means of screws 19. The lower edge of the blade 18 contacts with the floor surface and reduces the roughness. The scraper could be mounted on the carrier-frame and used with the smoothing-plane in place, but the operation would be too laborious although both the scraping and smoothing of the floor could thus be accomplished at one time.

In Figs. 7 and 8 I show a convenient form of sandpapering device that is adapted to be used in my machine too, especially when the said plane and scraper devices have performed their work, or when nothing but the final dressing of a floor is to be done and such sandpapering thereof only necessary. A rectangular block 20 is provided with an elongated longitudinal upright extension 21 that is practically a counterpart of the

plane-stock excepting it has no opening such as is provided for the bit and its adjuncts in said plane-stock. The same rear shouldered or depressed portion 13 is made in the upright extension 21, as in the plane-stock, and its coöperation with the inner shouldered side-walls of the carrier-frame is the same as that of the rear shouldered portion of the plane-stock. This upright extension 21 is shown in both Figs. 7 and 8, the latter view showing it in dotted-lines along its middle portion. A strip of ordinary sandpaper 22 is stretched over the lower surface of the block 20 and it has its four edges turned upward into engagement with the shouldered edges 23 of the block 20 for the securing or clamping engagement of a band 70 or the like 24 that is readily handled when it is desired to replace the strip or sheet of sandpaper at any time.

I claim:—

1. A floor-dressing implement comprising a hand-plane having a blade therein and a reduced or shouldered rear upper surface in the heel part of its stock, a carrier-frame having an elongated opening therein that has downwardly-facing shoulders of two levels to correspond to the two levels of the upper face of the plane and made in its side-walls for the ready and free accommodation of the plane from the bottom of the carrier-frame so that the bottom of the plane shall be at a lower level than that of the carrier-frame, and a rearwardly-extending propelling-handle detachably and adjustably secured at its fore end to the middle of said carrier-frame.

2. A floor-dressing implement comprising a rectangular, open carrier-frame adapted to readily and freely accommodate a hand-plane, a propelling, rearwardly-extending handle having a forked fore end and adapted to be adjustably connected to the carrier-frame, and a supplemental inclined scraper-blade whose length is that of the width of the carrier-frame at whose fore end it is mounted and thereby adapted to perform close-wall-and-corner work in the full dressing of said surface.

EDGAR D. FITZWATER.
